UNITED STATES PATENT OFFICE

LLOYD L. LEWIS, OF WOLLASTON, MASSACHUSETTS

STANCHION

Application filed April 6, 1931. Serial No. 528,173.

This invention relates to improvements in stanchions for supporting pipe lines or other things of similar character.

In recent years it has become more common to provide tunnels for large pipe lines instead of merely burying the lines in the earth. This has become especially common where a number of large pipe lines are to be laid parallel, as, for instance, where steam or hot water is to be conducted to and from buildings heated from a central heating plant. Ordinarily the tunnels are made large enough for a person to walk through and are lined with concrete inside. By this arrangement the pipes are readily accessible for inspection, repair, or replacement.

When a number of pipes are placed in such a tunnel, it is necessary that the pipes be properly supported at the required intervals and maintained in the desired positions with relation to each other and the walls of the tunnel.

For the purpose of supporting the pipes it has heretofore been customary to provide stanchions which, in general, comprised spaced vertical supports and horizontal bars upon which the pipes rested. When the stanchions were assembled in a tunnel, it was customary to attach the vertical members to the floor and ceiling of the tunnel by means of bolts set in expansion blocks in holes formed or drilled in the concrete of the floor and ceiling of the tunnel. The horizontal bars were usually screw-threadedly connected to the vertical members.

The installation of the required number of these stanchions for supporting pipe lines in a tunnel has proven a costly, slow, and troublesome item in the construction of the line. For instance, if it were an existing tunnel in which the stanchions were to be installed, it would be necessary to drill a number of holes in the concrete of the floor and ceiling of the tunnel for expansion bolts to hold the vertical members in place. Usually it would be necessary to drill at least eight holes for each stanchion. This has been found tedious and expensive work. In case the tunnel were being constructed simultaneously with the installation of the pipe

line, the necessary bolt inserts or sleeves could be formed or imbedded in the concrete as it was poured, but this requires a great deal of care in careful measurement to locate the bolt inserts or sleeves at the proper points, and adds to and complicates the work of building the tunnel.

This invention has for an object to provide an improved construction for stanchions whereby the work required for installation is materially reduced.

A further object of this invention is to provide an improved stanchion for supporting pipe lines or other things of similar character in tunnels which may be firmly and permanently installed in a tunnel without drilling or otherwise forming holes, depressions, or openings in the inner faces of the tunnel.

Another object of this invention is to provide an improved form of stanchion for supporting pipe lines or other things of similar character in tunnels, which is composed entirely of parts which may be cut to predetermined dimensions at the shops and assembled in position without modification of size, length, or in any other way.

Still another object of this invention is to provide an improved stanchion which is adapted to be permanently retained in position in a tunnel entirely by means of frictional engagement with the floor and ceiling of the tunnel.

A further object is to provide an improved stanchion which is adapted to be retained in position between the floor and ceiling of a pipe tunnel under a substantially uniform and unvarying compressive stress and in which the compressive stress is not materially altered by the variations of temperature to which it is liable to be subjected.

A further object of this invention is to provide an improved stanchion for supporting pipe lines in which longitudinal movement of the pipe lines relative to the stanchions due to expansion and contraction incident to temperature changes will be permitted without transmitting to the stanchions a force sufficient to deform the same or displace them from their proper positions in the tunnel.

While this invention is believed to be of

particular value in use in connection with pipe line tunnel stanchions, and this embodiment of the invention has been selected as illustrative thereof for the purpose of description in this specification, it is to be understood that the invention is not to be construed as limited to this embodiment, except as set forth in the appended claims.

In the drawings, Figure 1 is a front view 10 of a pipe line tunnel stanchion constructed in accordance with my invention.

Figure 2 is an enlarged view partly in section of a part of Figure 1.

Figure 3 is a view of an upper retaining 15 cup looking upwardly at the same as it is disposed in Figure 2.

Figure 4 is a side view of a cross-arm retaining cup as disposed in Figure 2.

Figure 5 is a bottom view of a cross-arm 20 retaining cup as disposed in Figure 2.

Figure 6 is a sectional view of the stanchion shown in Figure 1 taken on line 6—6.

Figure 7 is a front view partly in section 25 of a modified form of vertical support.

In the drawings, number 1 refers to a side wall of a tunnel through which a number of pipe lines 2 extend. The floor of the tunnel is indicated by numeral 3 and the ceiling by numeral 4. Usually the side walls, ceiling 30 and floor of pipe line tunnels are made of concrete.

The stanchion forming the subject of my invention comprises a pair of vertically disposed columns 5 and 6 which may be solid 35 metal or tubular. These columns 5 and 6 may be provided at their lower ends with external running threads as indicated at 7. The lower ends of columns are screwed into internally threaded openings 8 of metal castings 9. The lower face of each casting 9 is roughened as at 10, so as to increase its friction against the concrete floor 3 of the tunnel. These surfaces are preferably made rough when the castings are formed.

In the preferred form the upper ends of 40 the columns are not threaded, but are left plain. Upper column retainer cup castings 11 are also preferably formed with a roughened surface 12 for frictional engagement 50 with the ceiling of the tunnel. These castings 11 are formed cup shaped, that is, are provided with a central circular recess 13. This recess is adapted to receive and retain the upper end of a vertical supporting column 5 or 6. Before the end of a supporting column is inserted in recess 13, however, a strong spring washer 14 and a plain washer 15 are inserted in the recess.

For carrying the pipe lines, the stanchions 60 are provided with cross arms or bars 16 which are supported at their ends in cups 17 which may be secured to uprights 5 or 6 by U-shaped bolts 18. These cross arm supporting cups comprise a base plate 19 provided with a 65 vertically extending semicircular recess 20

adapted to conform to the shape of an upright column 5 or 6 upon which it is secured. The base plate is also provided with a number of bolt holes 21 properly positioned to receive the ends of U-shaped bolts 18 which secure 70 the cup to an upright. A semicircular flange 22 is formed on the base plate 19 and forms a cup 23 for supporting and retaining one end of a cross bar 16 upon which the pipe lines rest. The inside face of each cup 23 is made 75 relatively smooth and the cups are of such size that the ends of cross bars 16 will substantially fill them but may rotate relative thereto without binding or unnecessary friction. The ends of cross bars 16 are also free 80 of unnecessary roughness so that cross arms may rotate in the cups without transmitting a material force to the cups and the stanchions.

In a modified form of my invention the 85 upright columns are retained in position between the floor and ceiling of the tunnel by a somewhat different arrangement. As shown in Figure 7, the lower end of vertical supporting column 25 is screw-threadedly 90 received in a retainer casting which is similar to retainer casting 9 described in connection with the previously described embodiment. The upper end of column 25 is provided with a running thread 26 having the opposite pitch 95 to that on its lower end. The upper end is received in a retainer casting 27 which is substantially similar to member 9, but is provided with a running thread of opposite pitch from the thread of member 9. The spring washer 100 14 and plain washer 15 are omitted from retaining cup 27. In all other respects this modified form may be similar to the first embodiment described.

The operation of installing a stanchion 105 constructed in accordance with my invention is a relatively simple procedure. The bottom castings 9 may first be screwed on to the lower end of the upright columns 5 and 6 until the lower extremities of the columns are substantially flush with the bottom roughened surface of the castings. The uprights are then placed with their lower ends and the castings 9 carried thereby in the desired positions on the tunnel floor and are 110 disposed vertically. The upper retainer castings 11, with the spring washers 14 and plain washers 12 inserted in recess 13, are then placed in position on the upper ends of the columns 5 and 6. The next operation is 115 to unscrew the columns from the lower retainer castings 9, so that the columns will move upwardly and the upper ends thereof press into recesses 13 of the upper retainer cups 11 and engage plain washers 15. The upper retainer cups are thereby forced 120 against the ceiling of the tunnel, and the upper roughened surfaces 12 frictionally cooperate with the concrete ceiling 4 so as to prevent lateral displacement of the vertical 125 130

columns from their proper positions. As the upward movement of the columns continues, the spring washers are compressed to some extent but the unscrewing of the 5 columns from the lower castings is stopped before the spring washers are entirely flattened out. Thus, the vertical columns are retained under resilient compression and lateral displacement thereof is prevented by 10 the frictional engagement between the roughened surfaces of castings 9 and retainer cups 11 with the floor and ceiling respectively of the tunnel. The spring washers 14 have the function of yielding whenever 15 the columns become elongated from unusually high temperatures so as to prevent an excessive pressure being exerted on the roof. The spring washers also prevent the columns 5 and 6 from being subjected to 20 excessive compressive stress and the resulting tendency to buckle. When the columns become cold with incidental shortening, the spring washers will expand and compensate for the reduction in length so that the 25 columns will continue to be held under compression and the roughened surfaces of members 9 and 11 will be retained in frictional engagement with the floor and ceiling of the tunnel.

30 After the vertical columns have been firmly established in position, the cross-arm supporting cups 17 are secured on the columns at the proper height from the tunnel floor to give the pipes 2 to be supported the proper grade. The pipes 2 are then lifted into position and the cross bars 16 are placed with their ends in the retaining cups. The pipes may then be permitted to rest upon the cross arms.

40 In case it should be desired at some later time to disassemble a stanchion, the upright columns may be turned in the proper direction to screw the lower ends thereof further into bottom castings 9. This shortens the 45 length of the columns and relieves the pressure of the upper retainer cups against the ceiling and the stanchion may be lowered to horizontal position. In case the plain washers 15 were not used between the upper ends of the stanchions and the strong spring washers 14 it would sometimes be found that the sharp edge of the spring washers would cut into the metal of the end 50 of the columns and the retainer cups 11. In this event the washers would interfere with 55 turning of the columns in the direction necessary to withdraw the column ends from the retainer cups. It is to prevent this that the plain washers are used between spring washers and the ends of the columns.

60 When the pipe line is in service the temperature of the pipes will vary according to the temperature of the fluid being conducted and naturally the pipes will expand and contract with incidental movement longi-

tudinally. The outer surfaces of large pipes may sometimes be rough and somewhat irregular. In order that the movement of the pipes over cross bars 16 will not exert an excessive force tending to displace the stanchions, the ends of the cross bars and the inner surface of the retainer cups are made smooth so that the cross arms may rotate or roll with respect to the retainer cups.

70 The erection of a stanchion constructed in accordance with the modified form of my invention previously described is substantially similar to the procedure outlined above except with respect to the erection of the vertical columns 25. These columns are erected by screwing both the castings 9 and 27 upon the lower and upper ends of the columns. The columns are then disposed vertically and placed in the desired position in the tunnel. The castings 9 and 27 are held against rotation while the columns are turned in the proper direction to unscrew from both castings which are threaded with opposite pitch as has heretofore been explained. This forces the upper and lower castings upwardly and downwardly respectively and into frictional engagement with the ceiling and floor of the tunnel so as to bind the columns under compression in the desired position in the tunnel. The rest of the operation of 80 installing the modified form of stanchion is similar to the procedure described in connection with the other form.

85 Having described my invention, I claim:

90 1. A stanchion for supporting pipe lines 95 between vertically spaced surfaces comprising a pair of horizontally spaced vertically disposed standards, each having an end retaining member at each end for frictionally engaging the vertically spaced surfaces, a screw connection between one end of each standard and its corresponding retaining member for extending or retracting the length of the standard to adjust the frictional engagement with the vertically spaced surfaces, a spring between the opposite end of the standard and retaining member to maintain the frictional engagement at approximately a predetermined degree of pressure, a retainer bracket attached to each standard 100 intermediate its ends and a horizontally disposed pipe supporting rod having its ends supported in said retainer brackets.

105 110 115 120 125 130 2. A stanchion for supporting pipe lines between vertically spaced surfaces comprising a plurality of horizontally spaced vertically disposed standards, each having an end retaining member at each end for frictionally engaging the vertically spaced surfaces, a screw connection between one end of each standard and its corresponding retaining member for extending or retracting the length of the standard to adjust the frictional engagement with the vertically spaced surfaces, a spring between the opposite end

of the standard and retaining member to maintain the frictional engagement at approximately a predetermined degree of pressure, a retainer bracket frictionally attached to each standard intermediate its ends and a horizontally disposed rounded pipe support having its ends supported in said retainer brackets.
